United States Patent Office.

CYRUS HARRIS, OF RIVER POINT, RHODE ISLAND.

Letters Patent No. 92,189, dated July 6, 1869.

IMPROVEMENT IN SKEWERS FOR SPEEDER-BOBBINS.

The Schedule referred to in these Letters Patent and making part of the same.

To all whom it may concern:

Be it known that I, CYRUS HARRIS, S. W., of River Point, in the county of Providence, and State of Rhode Island, have invented a new and useful Improvement in "Skewers" for Speeder-Bobbins or Spools; and I do hereby declare that the following is a full, clear, and exact description of the same, reference being had to the accompanying drawings, making part of this specification, in which—

Figure 1 is an elevation of my improved skewer and section of the speeder-bobbin;

Figure 2 is an elevation of the said skewer separately;

Figure 3 is an elevation of the said bobbin separately; and

Figure 4 is a plan of the bottom or lower end of said bobbin.

Similar letters denote like parts in all the figures.

My invention relates to the construction of the skewer or spindle, upon which the bobbin or spool is held, and revolves within the creel of the speeder, as the roving is unwound therefrom and delivered to the spinning or twisting-apparatus of the machine; and

My said invention consists in constructing the said skewer with a shoulder or support near its top, or within the barrel of the spool or bobbin, which is also provided with a corresponding shoulder to fit and rest on the said shoulder of the skewer, for the purpose of cheapening the cost of the skewer, and to make it more durable and better adapted for any variation in the creels of different machines, and for other purposes.

Heretofore the skewer has been made with a narrow or thin flange at the bottom, of sufficient diameter to support the bobbin, the bottom of which rested upon this flange. This flange, as I have stated, was narrow or thin, necessarily so, to limit the space between the bottom of the bobbin and the step in the

creel, to afford all possible space for the admission of the full bobbin; and it not unfrequently happens in handling the full bobbin with the skewer inserted therein, that in the haste of substituting full bobbins for empty ones, the bobbin and skewer are dropped on the floor, and the thin flange thereby broken off, so that the skewer is thereafter useless.

It is also the fact that in forming the skewer with such a flange, a larger piece of wood is required, or else an additional piece is glued upon the bottom of the skewer to form such flange, which piece becomes loose from contact with oil and the heat of the room in which the machines are operated, and in consequence the flange thus formed cracks off and separates from the skewer, which is obviously attended with considerable trouble and expense.

Now, the construction set forth as my invention, dispenses with all this objection, and is otherwise of more practical utility and value.

In the drawings, fig. 2 represents my improved skewer, consisting of a plain cylindrical piece of wood, D, necked down to a tapering point, I, at the bottom, and with a shoulder, B, and a cylindrical stem, E, and tapering tip S.

Upon this skewer the bobbin K fits and rests, as shown in fig. 1, a shoulder, t, within the barrel of the bobbin, resting on the shoulder B of the skewer.

Having described my invention,

What I claim, and desire to secure by Letters Patent, is—

The skewer, constructed as herein described and shown, and provided with a shoulder, B, near its top, to afford a support for the bobbin or spool, for the purpose specified.

CYRUS HARRIS, S. W.
